UNITED STATES PATENT OFFICE.

GUSTAV E. JANSSON, OF WOLLASTON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS.

OIL-FILLED INSULATING BUSHING.

Application filed December 1, 1926. Serial No. 152,030.

This invention relates to insulating bushings for the protection of high tension leads of metal enclosed electrical apparatus and particularly to insulators of this type which are adapted to be filled with an insulating fluid or compound, such as oil.

Porcelain is generally used for the outer tubular casing of the bushing which forms a container for the insulating fluid within, and due to the great length of bushing required in high tension apparatus these tubes are necessarily made up of several sections secured together in a suitable manner to provide a long, fluid-tight insulating tube. Cement is employed to provide the mechanical bond between the several sections of the tube but, due to its porous structure, cement can not always be relied upon to provide a perfectly oil tight joint. Consequently, in oil filled bushings additional fluid sealing means must be provided.

Various devices have been proposed to supplement the cement at the joints between the tubes but most of these have failed to be durable in practice or for other reasons have been objectionable.

It is an object of this invention to provide a high tension multi-part insulating bushing with means by which fluid-tight joints are provided between the parts in an inexpensive and effective manner.

A still further object is generally to improve the construction and performance of oil filled insulating bushings.

Fig. 1 is an elevation partly in section of an insulator embodying the invention.

Fig. 2 is an enlarged sectional detail of the insulator of Fig. 1 in the vicinity of the supporting flange, showing the fluid tight joint between the two insulating sections.

Fig. 3 is a section of an insulator similar to Fig. 1 showing a modified form of oil seal.

As here shown, the insulating bushing embodying the invention comprises the upper insulating section 10 provided with the usual capes or petticoats 12, the lower insulating section 14 provided with external corrugations 16 at the lower end thereof, and the intermediate metal attaching collar, or sleeve

18, which surrounds the proximate ends of said sections 10 and 14. The upper insulating section comprises essentially a porcelain tube preferably having straight side walls

and being open at the top and bottom. The lower insulating section comprises a porcelain tube open at the top and tapered at its lower end to provide a restricted passage at the bottom.

The insulator is provided at the top with an oil reservoir consisting of a metal cylinder 20 which is secured in fluid tight relation to the open top of the upper insulating section 10. The oil reservoir is provided with a cap 24 which is screw-threaded to the upper end of said cylinder 20 and forms a cover for the reservoir. A glass cylinder 26 is disposed within said cylinder 20 and the oil level in the insulator and in the glass cylinder 20 is visible through suitable apertures 28 of the metal cylinder 20. Said reservoir cover 24 is provided with an upstanding projection 29 having an axial passage therein through which a conducting stud 32 is adapted to pass freely. Said opening is protected against entrance of water by a cover 34 which is screw-threaded on said conductor and which has a depending apron 36 surrounding the projection 29.

The restricted passage at the lower end of the insulating section 14 is provided with an axial bushing 38 secured therein by means of cement 40. Said conducting stud 32 is adapted to be screw-threaded through and extend beyond said bushing and a lock nut 41 is screwed onto the lower extended end thereof to prevent rotation of the stud in the bushing. An oil tight seal is provided at the lower end of the insulator by a packing 42 disposed between the lower end of said insulating section 14 and the nut 41.

The metal collar 18 is adapted to provide a mechanical connection between the upper and lower insulating sections and also to provide a support for the insulator and said collar is provided with an integral outstanding flange 44 by which the bushing is adapted to be secured to the casing 46 of an electrical apparatus. Said collar is adapted to be somewhat larger in diameter than the two insulating sections to provide an annular space therebetween to receive a body of cement 47 by means of which said upper and lower insulating sections are rigidly and permanently fixed within said collar 18. Annular grooves 48 are formed on the inner surfaces of said collar into which the cement may

enter, and these surfaces of the insulating sections which are surrounded by said collar may be roughened, thus enhancing the strength of the mechanical bond between the metal collar and the insulating sections. The cemented joint between the insulating sections 10 and 14 provides a permanent, unitary structure for the enclosing casing of the bushing which is adapted to remain intact when once assembled.

There is no necessity for subsequently breaking the joint between the sections since the open top construction permits the removal and assembly of the inner parts of the bushing through the top as set forth in my co-pending application Serial No. 110,126, filed May 19, 1926.

As previously stated, cement where used between sections of oil filled bushings cannot always be relied upon to maintain an effective oil tight seal thereat because of its inherent porous structure. Consequently it is necessary to provide additional fluid sealing means wherever the oil has access to the cement. In accordance with my invention an external coating of elastic, fluid-impervious material is provided at the top and bottom of the metal collar 18 as shown in Figs. 1 and 2. Previous to applying this coating, the porcelain surfaces to be covered preferably are somewhat roughened as by grinding, and annular grooves 52 are ground or otherwise formed in the outer surface of the insulating sections 10 and 14 just beyond the level of the body of cement 47 to avoid a sharp angle in the coating at the junction of the cement and the insulating section, and also to provide a more secure bond between the coating and the porcelain. The inner surface of said metal collar 18 may be provided with annular serrations 53, see Fig. 3, in the vicinity of the elastic coating if desired to increase the surface of adhesion and prevent any tendency of the coating to pull away from the metal surfaces upon expansion and contraction thereof.

Said fluid-impervious coating may comprise any tough, elastic inorganic substance such as a metal. In the embodiment of the invention herein shown, I have chosen to employ a metallic substance to provide the fluid sealing coating.

The metal for the coating material is applied by the hot metal spray process, by which the metal is deposited in a very thin continuous film of finely divided molten particles, which particles are forcibly thrown onto the surface and into the pores of the surface upon which it is directed, thereby forming a strong mechanical bond with the surface and the film, which, while preferably thin, is very strong and tenacious. The metal can be applied continuously until the required thickness of film has been deposited, the amount of metal which it is desirable to

build up in this manner depending upon the operating conditions to which the insulator is to be subjected; and the particular metal or alloy of metals employed will be governed, among other things, by the considerations of expansion and contraction of the associated parts of the insulator.

The metal coating or sheet is characterized by being fluid-impervious so that oil which may seep into the cement by capillary action is prevented from escaping from the outer surface thereof. The coating is closely adherent to all the surfaces and enters the pores and irregularities of the surfaces whereby it is, in effect, bonded thereto. The coating is flexible to permit a small amount of relative movement between the surfaces to which it is adherent without rupture and is ductile so that it can stretch the small amount necessary to prevent rupture.

The metal coating 54 at the top of said collar 18 extends from the collar 18 to a point beneath the lower cape of the insulating section 10, and the lower metal coating 56 is extended to a point below the level of the oil in the casing 46 of the electrical apparatus. A single turn of wire 58 of substantial diameter to which the metal coating will adhere is disposed about the lower insulating section 14 at this point to provide a suitable termination of the metal ground shield thus formed and also more evenly to distribute the electrical stresses at the end of said ground shield.

Fig. 3 is a modified form of the oil seal shown in Figs. 1 and 2 in which a soft protective packing or compound 60 is placed around the metal seal after which a second metal coating 62 is built up between the collar 18 and the first metal coatings 54 and 56. In this way an elastic and yielding film of metal is provided to supplement the outer metallic seal in case it should be by any chance broken by unduly rough treatment in transportation, or otherwise.

In disclosing the invention, I have shown the metal seal applied at the ends of the collar 18 which in the particular insulator shown is the most feasible construction since the seal is made after the assembly of the insulator and is accessible for inspection or repair. However, it is possible, and in some constructions practicable, to apply the metal coating directly to the juxtaposed ends of the insulating sections and to the exterior of the bushing in the immediate vicinity of the joint previous to cementing the supporting collar 18 in place. Various other modifications in the manner of applying the metal seal may be employed without departing from the scope of the present invention.

I claim:

1. An oil-filled insulating bushing including two adjacent sections, a fluid permeable body interposed between said sections having its inner surface in contact with the oil within

the bushing, and an elastic, fluid-impermeable metal coating covering the outer surface of said body.

2. An oil-filled insulating bushing having an insulating shell, an attaching sleeve surrounding the shell, a body of cement disposed between said sleeve and said shell and exposed at its inner surface to the oil in the bushing, and means providing a fluid-tight seal for the outer exposed surface of said cement body, said means comprising a coating of fluid-impervious metal adherent to the cement and also to the adjacent surfaces of said shell and said sleeve.

15 3. An oil-filled insulating bushing having an insulating shell, an attaching sleeve surrounding the shell, a body of cement disposed between said sleeve and said shell and exposed at its inner surface to the oil in the bushing, and means providing a fluid-tight seal for the outer exposed surfaces of said cement body, said means comprising a thin fluid-tight metal sheet closely conformed to the surfaces of the sleeve, cement body and shell and strongly adherent to said surfaces.

20 4. An oil-filled insulating bushing having an insulating shell, an attaching sleeve surrounding the shell, a body of cement disposed between said sleeve and said shell and exposed at its inner surface to the oil in the bushing, and means providing a fluid-tight seal for the outer exposed surface of said cement body, said means comprising a thin fluid-tight metal sheet closely conformed to the surfaces of the sleeve, cement body and shell and strongly adherent to said surfaces, said sheet being characterized by being flexible and ductile.

25 5. An oil-filled insulating bushing including a pair of spaced members having an interposed body of cement connecting them, which body is exposed at its inner exposed

surface to the oil in the bushing, and means to seal the outer exposed surface of the cement body against escape of oil therefrom comprising a thin and flexible oil-tight metal coating covering the outer end of the cement body, and the adjacent surfaces of said spaced members and strongly adherent therewith.

45 6. An oil-filled insulating bushing having two axially aligned insulating members, a collar disposed around the proximate ends of said members and spaced therefrom, a body of cement contained in the space between said collar and said members to bind said collar and said members together, and a continuous metal coating disposed at the top and bottom of said collar and strongly adherent therewith and with said insulating members and forming a fluid-tight seal thereat.

50 7. An oil-filled insulating bushing including a pair of spaced members, a porous binder interposed between said members and exposed at its inner surface to the oil in the bushing, a fluid-impermeable sealing material overlying the outer surface of said binder, and a thin fluid-impermeable metal sheet overlying said sealing material and the adjacent surfaces of said members and having a fluid-tight and strong mechanical bond therewith.

55 8. An insulating bushing having an insulating oil-containing shell, a metal collar surrounding said shell intermediate its ends, a body of cement located between said collar and shell and exposed to the oil in the shell, a metal ring surrounding said shell below said collar, and a metal coating connected intimately with said collar and shell and with said ring and overlying and forming an impervious fluid seal for said cement bushing between said collar and shell.

60 In testimony whereof, I have signed my name to this specification.

GUSTAV E. JANSSON.
